ATTORNEY.

UNITED STATES PATENT OFFICE

WALTER P. JOBSON, OF LOUISVILLE, KENTUCKY

FAN

Application filed May 11, 1929. Serial No. 362,215.

This invention relates to a hand fan, the object being to produce an article wherein the blade and handle are made from an integral sheet of material with means for locking same upon itself so as to form a rigid and enduring structure.

The invention consists in stamping or cutting a sheet of material, preferably cardboard, in a single piece to produce a blank 10 which may be distributed in flat form and subsequently manipulated so as to produce a complete substantial fan with a handle made from the integral sheet.

The functions of the various component 15 members will appear from the following description in connection with the drawings in which—

Figure 1 is a front view or outline made from a flat sheet, the full lines indicating 20 the cut through edges and the dotted lines the hinges.

Fig. 2 is an end view of Fig. 1, after the sheet has been folded and locked in place.

Figs. 3 and 4 are similar views of a modified form and Fig. 5 is a fragmentary plan view of same.

A sheet, 1, of suitable material is cut to substantially the outline as shown with perforations 2a, 2b, from flaps 2 attached to 30 handle 4, into which tongues 3a, 3a, cut from flap 3 can be inserted when the handle is folded along the dotted lines 4a, 4a, which act as hinges. To accomplish this it is necessary to bow or arch the entire sheet as shown 35 in Fig. 2. After this operation which includes the interlocking of the handle parts just referred to, the handle and blade of the fan will be held in an arched or bowed form which gives a maximum rigidity for the materials employed and supplies a handle which 40 is not only comfortable to the palm and fingers of the human hand, but also produces a relatively long-lived fan.

In Fig. 3 the interlocking groove 2 and 45 tongue 3 have been omitted and the plain

flaps 5, 5 have been substituted which are so proportioned that when bent along lines 4a, 4a, and squeezed produces the bowed or arched form as shown in Fig. 4. A rubber band 6 which has been previously placed in 50 slots 7, 7, made into the handle 4 is removed and placed around the entire handle to secure same in lieu of the interlocking arrangement employed for Figs. 1 and 2.

While I prefer to use the structure shown 55 in Fig. 1 which admits of flat production for the purposes of shipping in large quantities, it may be desirable to use an external securing means like the rubber band, or possibly a standard paper clip when a very low grade 60 material may be employed for making the fan.

Other modifications will suggest themselves to one versed in the art of manufacturing fans for ordinary uses or advertising purposes. Therefore, I do not limit myself other than by the attached claims.

I claim:

1. A fan comprising a blade and a handle section made of an integral sheet of material, 70 a flap on each side of said handle section, each of said flaps being of less width than the handle section, and means for holding the flaps in overlapping relation whereby the handle section is bowed outwardly to 75 hold the blade in a warped form.

2. A fan comprising a blade and a handle section made of an integral sheet of material, said handle section being provided with a flap on each of its side edges, each of said 80 flaps being of less width than the handle section and foldable in overlapping relation on the handle section to curve the sheet of material, and means for interlocking said flaps.

3. A fan comprising a blade and a handle section made of an integral sheet of material, the handle section having a flap on each side edge thereof, each of said flaps being of less 85 width than the handle section, and means for holding the flaps in overlapping relation 90

with the handle section to form therewith a hollow reinforced handle.

4. A fan comprising a blade and a handle section made of an integral sheet of material, the handle section being provided with a flap on each side edge thereof, and means for holding the flaps in overlapping relation with the handle section, each of said flaps being of less width than the handle section, said holding means and flaps constraining the handle section and blade to form a continuous arched structure.

In testimony whereof I affix my signature.

WALTER P. JOBSON.
